(57) CLAIM

The ornamental design for an exercise stand frame, as shown and described.

DESCRIPTION

FIG. 1 is a perspective view of an exercise stand frame showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a perspective view of the exercise stand frame shown with additional attachment; and,

FIG. 9 is an exploded perspective view thereof.

Broken lines in the drawings depict portions of the exercise stand frame that form no part of the claimed design.

1 Claim, 9 Drawing Sheets
